FIG. 1.

FIG. 2.

FIG. 5.

FIG. 6.

FIG. 4.

FIG. 7.

Inventor
Louis F. Landa,
By his Attorneys
Edgar Tatte & Co.

UNITED STATES PATENT OFFICE.

LOUIS F. LANDA, OF FLUSHING, NEW YORK, ASSIGNOR OF ONE-FOURTH TO WILLIAM F. SCHMALKUCHE AND ONE-FOURTH TO WILLIAM F. SCHMALKUCHE, JR., BOTH OF FLUSHING, NEW YORK.

SPARK-PLUG.

1,340,232.

Specification of Letters Patent.

Patented May 18, 1920.

Application filed September 13, 1918. Serial No. 253,870.

To all whom it may concern:

Be it known that I, LOUIS F. LANDA, a citizen of the United States, and residing at Flushing, L. I., in the county of Queens and State of New York, have invented certain new and useful Improvements in Spark-Plugs, of which the following is a specification, such as will enable those skilled in the art to which it appertains to make and use the same.

This invention relates to what are known as spark plugs used in connection with internal combustion engines, and the object of the invention is to simplify the construction of devices of this class by forming the metallic body portion thereof of two approximately similar parts joined longitudinally of said body; a further object being to provide a core for devices of the class specified which is composed of fireproof and waterproof material and which is placed between the separate parts of the body portion and held therebetween by the means for securing the separate parts of said body portion together; and with these and other objects in view the invention consists in a device of the class and for the purpose specified, constructed and operating as hereinafter described and claimed.

The invention is fully disclosed in the following specification, of which the accompanying drawing forms a part, in which the separate parts of my improvement are designated by suitable reference characters in each of the views, and in which:—

Figure 1 is a side view of my complete spark plug shown in position for use;

Fig. 2 a section on the line 2—2 of Fig. 1;

Fig. 3 a bottom plan view of the plug as shown in Figs. 1 and 2;

Fig. 4 an inside view of one of the metallic body parts detached;

Fig. 5 a detail view of the core portion of the plug with part of the construction broken away and in section;

Fig. 6 a detail sectional view of the core of the plug but showing a modification; and,

Fig. 7 a view similar to Fig. 3 but with part of the construction broken away and in section and showing the modification shown in Fig. 6.

In the practice of my invention, as shown in Figs. 1 to 5 inclusive, I provide a spark plug having a metallic body 10, composed

of two approximately similar parts joined centrally and longitudinally by pins and recesses as shown at 11 in Fig. 4, and said body comprises a top conical portion 12 at the base of which is an annular portion 13 below which is a hexagon shank 14 joined with an externally threaded and reduced sleeve 15 by a beveled portion 16. Each of the parts of the body 10 are provided with top and bottom bores 17 and 18 joined by an enlarged cylindrical bore 19, as shown in Fig. 4, and these bores are adapted to receive the core 20 shown in detail in Fig. 5.

The core 20 is preferably composed of a composition having asbestos as a base, which produces a fireproof as well as waterproof core, and the composition employed and method of making such core is described and claimed in a co-pending application filed of equal date herewith. Another advantage of constructing the core 20 of a composition having asbestos as a base produces a non-breakable core or one which would withstand a greater strain or shock than porcelain or other similar material employed for this purpose.

The core 20 consists of an enlarged cylindrical body 21 at the top of which is a reduced neck 22 having an enlarged semi-spherical cap 23 at the top of which is a shank 24, having an angular cross head 25. At the bottom of the enlarged cylindrical portion 21 is a rounded tip or projection 26, and when the core 20 is placed between the separate parts of the body portion 10 of the plug, the enlarged portion 21 fits within the enlarged cylindrical bores 19 and the reduced neck 22 fits in the bores 17, while the tip or projection 26 extends downwardly into the bores 18 as clearly illustrated in Fig. 2 of the drawing, in which figure it will be noted that the semi-spherical head 23 rests upon the top face 27 of the separate parts of the body portion 10 and an annular convex portion 28 is provided in the core 20 at the top of the neck 22 as clearly shown in Figs. 2 and 5 of the drawing, into which cement may flow in sealing the separate parts of the plug together, as hereinafter set out.

A heavy wire 29 is secured centrally of the core 20 or embedded therein in the process of molding the same, and said wire is held against movement in said core by a

plurality of twists or bends 30 therein, and the upper end of the wire 29 is provided with a cross head 31 mounted in a transverse aperture 32 in the angular cross head 25, and in connection with which the ends 33 of a spring contact device 34 operate as shown in Fig. 1 to transmit the current from the magneto to the wire 29. The lower end of the wire 29 is extended through the tip 26 of the core 20 and bent into hook-shaped form as shown at 35, and the free end 36 thereof is adapted to coöperate with a contact pin 37 secured in the wall of the bore 18 in radial alinement with the end 36 of the wire 29, and this construction forms the spark gap for the plug.

In connecting the separate parts of the plug prior to using the same, the core 20 with the wire 29 therein is provided with a 20 coating of liquid or plastic asbestos, this coating being applied principally upon the neck 22 and enlarged portion 21 of said core, after which the same is placed within one of the separate parts of the body portion 25 10, after which the other of said body parts is placed upon said core and the first named body part, after which a suitable packing and lock ring 38 is passed over the reduced and threaded sleeve portion 15 upwardly 30 onto the beveled portion 16 of the separate parts of the body portion 10 to lock said parts together. By subjecting the plug connected in the manner above set out gradually to a predetermined degree of heat, the 35 core will be permanently cemented within the separate parts of the body portion, and it will be understood that said asbestos cement may also be applied to the abutting faces of the separate parts of the body portion 10 which will permanently secure the 40 separate parts of the plug together, or until said parts are separated by force.

With a plug constructed in the manner above set out there will be no need for repair, or replacement unless the wire 29, or the hook-shaped end 35 thereof, should be broken off by accident, or otherwise, in which event a new core may be substituted for the old one, but unless damage is made 50 to the wire 29 there will be little chance of other breakage due to the strength of the core 20 when constructed of an asbestos composition. It will also be noted that I provide a spark plug which is composed of 55 four parts, namely, two body portions, a core and means for locking the separate parts of the body portions together.

In Figs. 6 and 7, of the drawing, I have shown a slight modification which consists 60 in embedding within the core 20 an annular contact wire 39 which is adapted to make contact with the walls of the enlarged cylindrical bore 19. The contact wire 39 is provided with inwardly directed portions 40 65 having downwardly directed extensions 41

joined by a cross head 42, which is slightly curved centrally thereof as shown at 43 in Fig. 7, and the protruding ends of the wire 29 in the core 20 extends straight downwardly as shown at 44, instead of being 70 hook-shaped in form as shown at 35, and which coöperates with the curved portion 43 of the cross head 42.

With the construction shown in Figs. 6 and 7 the spark circuit of the plug, or the 75 jump or cross over thereof is all contained within the core, and this would be of advantage in the event of the breaking of either of the circuit conducting wires which would merely mean the replacement of a 80 new core, while the construction shown in Figs. 1 to 5 inclusive, it would mean the replacement of a new core or a new body portion. While I have shown certain details of construction for carrying my invention into 85 effect and have stated that the core 20 is preferably composed of a composition containing asbestos as a basis, it will be understood that my invention is not limited to these details of construction, and various 90 changes therein and modifications thereof may be made, within the scope of the appended claims, without departing from the spirit of my invention or sacrificing its advantages.

Having fully described my invention, what I claim as new and desire to secure by Letters Patent, is:—

1. A spark plug comprising a body portion, means for retaining a core within the 100 body portion, said core being composed of a non-bearable fireproof and waterproof material having asbestos as a base, a circuit wire embedded in said core, one end of said circuit wire being provided with a cross 105 head, a spring contact detachably connected with the core and coöperating with said cross head and the other end of said wire protruding through the core and coöperating with the body portion through a suitable circuit carrying element.

2. A spark plug comprising a body portion composed of two approximately similar parts, the inner or abutting faces of which are provided with a plurality of recesses, a 115 core mounted in the recesses of the body portion, means for holding the separate parts of the body portion together to retain the core therein, said core being composed of a material having asbestos as a base, a 120 wire mounted in said core against displacement, one end of said wire protruding through the core and coöperating with the body portion through a circuit carrying element, and a tensional contact device coöperating with the other end of said wire.

3. A spark plug comprising a body portion composed of two approximately similar parts, which when joined together form a 125 conical head, a hexagon shank and a re- 130

duced externally threaded sleeve, the abutting faces of the body portion being recessed to form top and bottom bores, and a central enlarged annular bore, a core comprising an 5 enlarged annular portion adapted to fit in the enlarged annular bore, said core being provided with an upwardly directed reduced neck and a downwardly directed tip which fits in the upper and lower bores of the body portion respectively, a semi-spherical cap at the top of the neck of the core above which is a reduced neck having a cross head, a wire embedded in the core and extending from the cross head downwardly 10 and through the tip end thereof, a tensional contact device detachably connected with the cross head of the core and adapted to make contact with the upper end of said wire and the protruding end of said wire 15 being adapted to coöperate with a circuit carrying element in the body portion.

4. A spark plug comprising a body portion divided centrally and longitudinally

into two similarly formed and detachably connected parts, the abutting faces of which 25 are provided with recesses which when the separate parts of the plug are placed together form a chamber the central portion of which is enlarged, the separate parts of the plug when placed together forming a 30 central external angular portion, an externally threaded portion and a head portion, a one-piece core adapted to be contained in the chamber formed in said parts, and a ring member adapted to be passed over said 35 externally threaded portion for holding the separate parts of the body portion together to retain the core therein.

In testimony that I claim the foregoing as my invention I have signed my name in 40 presence of the subscribing witnesses this 11th day of Sept., 1918.

LOUIS F. LANDA.
